Inventor

Sidney J. V. Bovey

By Frank Thomas, Atty

UNITED STATES PATENT OFFICE.

SIDNEY J. V. BOVEY, OF CHICAGO, ILLINOIS.

SPARK PLUG.

Application filed November 26, 1920. Serial No. 426,349.

To all whom it may concern:

Be it known that I, SIDNEY J. V. BOVEY, a citizen of the United States, residing at Chicago, in the county of Cook and State 5 of Illinois, have invented new and useful Improvements in Spark Plugs, of which the following is a full, clear, and exact description.

My invention relates to improvements in 10 spark-plugs for internal combustion engines, and particularly for the gas engines used in automobiles, airplanes, motor boats, motor trucks, etc.

In view of the differences in the sizes of 15 socket-wrenches, the differences in the sizes of the spark-plugs, and the differences in diameter of the polygonal-shaped sides of the metallic casing of the plug, it is oftentimes difficult to match the wrench with the plug 20 and because of the differences to manipulate them.

The object of my invention is to so construct the exterior of the upper exposed portion of the metal casing of the plug, that a 25 socket-wrench of any of the conventional sizes can fit onto the same and enable the plug to be screwed into or out of the spark-plug opening in the cylinder of the engine, regardless of the size of the bore of said 30 socket-wrench. This I accomplish by the means hereinafter fully described and as particularly pointed out in the claims.

In the drawings:

Figure 1 is a side view of one form of 35 my invention.

Figure 2 is a plan view of the same.

Figure 3 is a side view of another form 40 of my invention.

Figure 4 is a plan view thereof.

Referring to Figures 1 and 2 of the drawings, 5, represents the metallic axial electrode of the spark-plug; 6, porcelain or other insulation surrounding the same between its exposed ends, and 7 represents the 45 metallic casing. The relative function of these parts of the plug are the same as those in spark-plugs now in extensive use, and, with the exception of the upper outer exposed portion of the metallic casing, the

construction and the assembling of said parts 50 is the same.

The widest portion of the spark-plug is about its center of length, and below this widest part the casing is reduced in diameter to provide a shoulder 8, and an exteriorly screw-threaded barrel 9. Above this widest portion the casing is provided with a series of circumferential flanges 10, the diameters of which are gradually increased from the uppermost to the lowermost, that 60 is, each flange is less in diameter than the one below it, and the outer edges of these flanges are made hexagonal similar to that of a nut, so that a socket-wrench the hexagonal socket of which is greater in diameter 65 than the uppermost flange 9, will fit on one of the flanges below the same. It is the intention to make the diameter of the uppermost flange such that the smallest socket-wrench will fit thereon, and to make the 70 diameter of the intervening flanges such that they can be operatively engaged by other socket-wrenches the diameter of whose sockets come between that of the largest and smallest flanges.

In Figures 2 and 4 of the drawings, I 75 show another form of my invention. The construction of this changed form is substantially the same as that hereinbefore described excepting that the upper portion 20, 80 of the casing above its widest center of length is made hexagonal and above a certain point 21 is shaped like a truncated six-sided pyramid, substantially as shown in the drawings.

In use, when it is desired to screw or unscrew the plug, the socket-wrench is slipped down over the upper part of the casing and no matter what the diameter of its socket is, it will engage and fit upon one of 90 the flanges of the form of plug first described or on the pyramidal sides or base of the second form and enable the same to be manipulated.

What I claim as new is:

1. The combination with a spark-plug comprising an electrode, an insulation therefor, of a metallic casing surrounding the

same the exterior of which above the widest portion of its length is provided with several individual engaging polygonal transverse sections of different diameters.

5. 2. The combination with a spark-plug comprising an electrode, an insulation therefore of a metallic casing surrounding the same the exterior of which above the widest portion of its length is provided with a plurality

of individual circumferential polygonal flanges each of which is greater in diameter than the flange above it.

In witness whereof I have hereunto set my hand this 18th day of November, 1920.

SIDNEY J. V. BOVEY.

Witnesses:
